UNITED STATES PATENT OFFICE

160,686

FIREPLACE GRATE

Narcisse C. Bergeron, Oakland, Calif.

Application October 19, 1949, Serial No. 5,570

Term of patent 14 years

(Cl. D31—18)

To all whom it may concern:

Be it known that I, Narcisse C. Bergeron, a citizen of the United States, and a resident of the city of Oakland, county of Alameda, State of California, have invented a new, original, and ornamental Design for a Fireplace Grate, of which the following is a specification, reference being had to the accompanying drawing, forming part thereof and wherein the figure is a perspective view showing my new design of a fireplace grate.

I claim:

The ornamental design for a fireplace grate, as shown.

NARCISSE C. BERGERON.
